UNITED STATES PATENT OFFICE.

MARION R. CASEY, OF CLINTON, SOUTH CAROLINA, ASSIG NOR TO CLINTON CAM COMPANY, OF CLINTON, SOUTH CAROLINA, A CORPORATION OF SOUTH CAROLINA.

CAM.

1,219,249.

Specification of Letters Patent. Patented Mar. 13, 1917.

Application filed May 25, 1916. Serial No. 99,779.

To all whom it may concern:

Be it known that I, MARION R. CASEY, a citizen of the United States of America, and a resident of Clinton, county of Laurens, State of South Carolina, have invented certain new and useful Improvements in Cams, of which the following is a full and clear specification.

This invention has relation to the type of cam patch covered by my Patent 1,177,304, dated March 28, 1916, in which a worn portion of the periphery of the cam is bridged by a patch plate bolted to the side of the cam body and having its periphery in alinement with the periphery of the cam, this patch being secured to the cam body by means of a pair of bolts, one at each end of the patch plate.

The object of the present invention is to so construct the patch plate that it may be secured in place by but a single bolt, usually the bolt that secures the cam point or toe to the cam body, as more fully hereinafter set forth.

25 In the drawings—

Figure 1 is a view of one of the styles or types of cam to which my device is applicable;

Fig. 2 is a side elevation of the same cam, provided with my patch device;

Fig. 3 is a radial section through the line 3—3 of Fig. 2;

Fig. 4 is a section through the line 4—4 of Fig. 2; and

Fig. 5 is a perspective view of the cam patch detached.

Referring to the drawing by reference characters, *a* designates the usual toe or point member which is bolted to the cam body in the usual manner by a bolt *b*. The rim of the cam is connected to the hub by means of spaced spokes *c*. The patch plate *d* is removably fastened to one face of the cam body by means of the aforesaid bolt *b* at one end, and, at the other end, by means of a lip or lug *e* engaging behind one of the adjacent spokes.

This patch is adapted to bridge the worn parts *f* (shown in Fig. 1) of the periphery of the cam just back of the toe *a*, and the parts are so proportioned that when the patch plate is locked in position against the

cam, the peripheral edge or face of the patch plate will bridge the worn part and virtually form a continuation of the peripheral surface proper of the cam body. Preferably, the inner face of the cam plate is shaped to fit within the sector-shaped opening between the spokes, so as to thereby assist in rigidly holding the patch in position.

I have illustrated my device as applied to a type of cam which wears most at a point back of the toe member. It will be understood that the patch plate is to be shaped to suit the necessities of the cam to which it is to be applied, and it will therefore be understood that I do not restrict myself to any particular form of patch plate or to any particular style of cam, so long as the cam body is provided with a hole or recess through which the locking lip or lug may be passed to enable it to engage the side of the cam opposite to that against which the cam patch bears.

Having thus described my invention, what I claim is:

1. In combination with a cam having an opening in its body portion, a patch plate and a bolt for attaching one end of said plate to the cam body, said cam plate being provided with a lip or lug extending through said opening and engaging the opposite face of the cam body, whereby the patch plate is removably locked in position against the cam body by a single bolt.

2. The combination with a cam having a removable toe member and a bolt for fastening the toe member to the cam body, of a patch plate having one end secured to one side of the cam body by the aforesaid bolt and having its other end extending through an opening in the cam body and engaging behind the opposite face of the cam body, said patch plate having a peripheral surface in alinement with the peripheral surface of the cam.

3. In combination with a cam body having an opening therein at a distance from its periphery, a patch plate having on one face an enlargement shaped to fit in said opening and having its periphery in alinement with the periphery of the cam body, and means for fastening the patch plate removably to the cam body.

4. In combination with a cam body having an opening therein, a patch plate having one face shaped to fit in said opening and having its periphery in alignment with the periphery of the cam body, and means for fastening the patch plate removably to the cam body, said means consisting of a bolt clamping one end of the patch to one face

of the cam body and a lip engaging the opposite face of the cam body.

In testimony whereof I hereunto affix my signature.

MARION R. CASEY.
